(57) **CLAIM**

The ornamental design for a lower leg component for utility sink, as shown and described.

DESCRIPTION

FIG. 1 is a top perspective view of a lower leg component for a utility sink, showing my new design;

FIG. 2 is a bottom perspective view of the lower leg component shown in FIG. 1;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left-side elevational view; the right side view is

a mirror image thereof.
The broken lines in the drawings show the portions of the lower leg component for utility sink that form no part of the claimed design.
